United States Patent

Des. 235,895

Patented July 15, 1975

235,895

SOUVENIR BATON OR THE LIKE

Edward W. Reed, 52 Redwood Ave.,
Edison, N.J. 08817

Filed Nov. 26, 1973, Ser. No. 418,861

Term of patent 14 years

Int. Cl. D21—01

U.S. Cl. D34—5 BC

The sole figure is a perspective view of a souvenir baton showing my new design. The suspended token is a flat symmetrical disc with the same appearance on both sides.

I claim:

The ornamental design for a souvenir baton or the like, as shown and described.
